(57) **CLAIM**

The ornamental design for a mesh panel, as shown and described.

DESCRIPTION

FIG. 1 is a perspective view of a mesh panel illustrating a first embodiment of our new design;

FIG. 2 is a front elevational view thereof; the rear being a mirror image;

FIG. 3 is a top plan view thereof;

FIG. 4 is a bottom plan view thereof;

FIG. 5 is an end elevational view thereof; the other end being a mirror image;

FIG. 6 is a perspective view of a mesh panel illustrating a second embodiment of our new design;

FIG. 7 is a front elevational view thereof; the rear being a mirror image;

FIG. 8 is a top plan view thereof;

FIG. 9 is a bottom plan view thereof; and,

FIG. 10 is an end elevational view thereof; the other end being a mirror image.

The broken away symbols in the drawings indicate that any portion of the article beyond what is shown forms no part of the claimed design. The broken lines shown on the ends of the mesh panel represent the bounds of the claimed design and form no part thereof.
